FRANCIS H. BROWN, OF PHILADELPHIA, PENNSYLVANIA.

METHOD OF EFFECTING AND REGULATING COMBUSTION IN FURNACES.

1,247,215.

Specification of Letters Patent.

Patented Nov. 20, 1917.

Continuation of application Serial No. 662,814, filed November 28, 1911. This application filed July 8, 1913, Serial No. 777,811. Renewed April 18, 1917. Serial No. 163,034.

To all whom it may concern:

Be it known that I, FRANCIS H. BROWN, a citizen of the United States, residing at Philadelphia, in the county of Philadelphia, State of Pennsylvania, have invented a new and useful Method of Effecting and Regulating Combustion in Furnaces, of which the following is a specification.

My present invention, in its broad and generic scope, consists of a novel method of effecting and regulating combustion in a furnace or in furnaces, operating under an induced draft, naturally or mechanically produced, whereby a single fire or a plurality of fires with beds of fuel of different and varying thickness will automatically maintain substantially the same rate of combustion and also a substantially fixed or constant difference of draft pressure or tension above and beneath the bed or beds of fuel, and thereby reduce to a minimum the amount of air employed to produce combustion.

It further consists of a novel method of regulating combustion wherein the variations of load of a furnace or furnaces or variations in steam pressure are utilized to automatically vary the conditions within the furnace or furnaces or the heat zone thereof and then the conditions varied in this manner are utilized together with the varying resistance offered to the introduction of draft beneath the bed of fuel to automatically vary the amount of draft for combustion. The varying resistance offered to the introduction of draft beneath a bed of fuel may be the varying thickness of the bed of fuel, a partially closed damper, or a combination of such conditions.

The damper or dampers, which are operated to vary the conditions within the furnace, may be manually controlled to vary the conditions within a furnace or furnaces and then the introduction of draft beneath the bed or beds of fuel automatically controlled in accordance with the varying conditions within the furnace thus formed, and such operation is within the spirit and scope of my invention.

Each exhaust flue or stack may discharge individually, as shown, or they may all be connected to a main exhaust flue or chimney, in which latter case the means for mechanically inducing the draft or for varying the

condition in the furnace would be located in the main exhaust flue, as seen in Fig. 8, and such operations are within the scope of my invention.

In the broad spirit and scope of my invention, it is immaterial whether a natural or mechanical induced draft is employed. Many different types of mechanism can be used to produce the mechanical induced draft, and it is immaterial whether hand firing or mechanical stokers or fuel feeding means are employed, and the type of fuel used, whether solid, liquid, gaseous, or a combination of any of the same is also immaterial, and it is to be understood that my claims herein are to be construed as of corresponding scope.

In a copending application, I have disclosed and generically claimed a novel method of regulating combustion, wherein the variations of load on a furnace or furnaces are utilized to automatically vary the conditions within the furnace or furnaces, and then the varying conditions within the furnace or furnaces are utilized to automatically control the introduction of draft for combustion, and my present invention, while of the same generic scope, is differentiated from the above in that I dispense with the necessity of employing a forced draft and employ in lieu thereof an induced draft, either natural or mechanical.

It further consists of a novel method of regulating combustion, whereby high temperatures may be maintained within the furnace and a maximum efficiency at all rates of combustion.

Other features of advantage and operation will more clearly hereinafter appear in the detailed description of my invention.

For the purpose of illustrating one manner of advantageously carrying out my novel method in practice, I have shown herein forms thereof which have been found in practice to give satisfactory and reliable results, although it is to be understood that the various instrumentalities of which my invention consists can be variously arranged and organized and that my invention is not limited to use with the precise arrangement and organization of these instrumentalities, as herein shown and described.

Figure 1 represents a sectional elevation of one type of a furnace in conjunction with

which my novel method can be advantageously employed.

Fig. 2 represents a sectional elevation of a portion of Fig. 1.

5 Fig. 3 represents a sectional elevation of the pressure regulator seen in Fig. 1.

Fig. 4 represents a sectional view of another type of mechanism for producing a mechanically induced draft.

10 Fig. 5 represents a sectional view of the parts seen in Fig. 1, but showing a hand firing arrangement instead of the mechanical stoker seen in Fig. 1.

Fig. 6 represents an elevation, partly in 15 section, of Fig. 5.

Fig. 7 represents a perspective of certain details of construction, seen in Fig. 5.

Fig. 8 represents a sectional elevation of 20 a portion of furnaces having the individual exhaust conduits discharging into a main exhaust conduit, or stack.

Similar numerals of reference indicate corresponding parts in the figures.

Referring to the drawings:—

25 1 designates furnaces of any desired or conventional type and which, in the present instance, are each provided with an ash-pit 2, a traveling grate 3, which acts as a stoker or fuel feeding means, a combustion chamber or heat zone 4 on one side of a bed of fuel 5, a boiler 6, an individual stack 7, and a main header 8, it being understood that, in the present instance, I have shown a 30 battery of boilers and a plurality of furnaces, as will be best understood by reference to Figs. 5 and 8. 9 designates the main draft conduit, to which draft is supplied under its natural or atmospheric pressure, provided with a manually controlled damper 10

40 and from conduit 19 lead branch conduits 11, which are in communication with the ash-pits 2 of their respective furnace, and each of which is provided with a manually controlled damper 12. 13 designates a steam 45 conduit communicating with the main header 8 and with a steam regulator 14 of any desired or conventional type, and illustrated as of the well known diaphragm type, said conduit 13 being provided with a manually controlled valve 15. 16 designates 50 a rod which is actuated in the well known manner, by the diaphragm, in accordance with the variations in the steam pressure to rock the lever 17 on its pivot 18, said lever 17 being provided with an adjustable counterbalance 19, whereby the effective 55 weight of the counterbalance may be varied as desired.

60 20 designates a cable of any desired nature which passes over pulleys 21 and 66 and is connected with the pulley 66, which latter is fixed on a shaft 67 mounted in any desired manner. 68 designates cables connected with pulleys 69 on the shaft 67 so as to be

actuated in unison therewith, said cables 65 also passing around pulleys 22, which latter are operatively connected with dampers 23 mounted in exhaust conduits 7 of the different furnaces. 24 designates an adjustable counterbalance for a damper 23. The lever 70 17 is also connected with an arm 25 which automatically controls the operation of a motor of any desired type but shown for purposes of illustration of the well known Spencer type which has been on the market 75 for many years.

The lever 25 has one end thereof pivoted to a link 70, said link being also pivoted to an extension from the piston 112, with which latter co-operates a valve stem 113, 80

which is pivoted to the lever 25. The motive fluid is admitted to the piston chamber 114, through the valve controlled conduit 115, and is discharged from the piston chamber through the conduit 116, which latter is 85 pivoted to a lever 117 fulcrumed at 118 with a bracket 119, it being understood that the lever 117 has connected therewith the cable 20. The lever 117 is operatively connected with a valve 120 located in the steam conduit 28, which latter leads to the engine 29 controlling the operation of the fuel feeding mechanism, which for purposes of illustration, has been shown as consisting of a traveling grate 3. The steam conduit 28 is provided with controlling valves 30 and 31. A branch conduit 32 may also be provided, if desired, with a valve 26 which communicates with a conduit 27, which also communicates with the steam conduit posterior to the valve 30, and said conduit 27 is provided with a controlling valve 121.

100 Each of the furnaces 1 is provided with a pressure regulator 33 of any desired or conventional type, but which for convenience of illustration, I have preferred to show as corresponding to one of my prior Patents 883,283, patented March 31st, 1908, except that I have shown in addition thereto a novel damping means, such as is illustrated and generically claimed in one of my co-pending applications Serial No. 664,613, filed December 8th, 1911, and the construction and operation thereof will be best understood by reference to Fig. 3.

110 34 designates a pivoted member normally maintained in a substantially horizontal position by means of an adjustable counterbalance 35, whereby said member may be set to operate at any desired standard of 120 pressure. The member 34 includes an inverted container 36 which extends into a container 37, in which liquid, such as for example, water, is kept at a constant level in a manner hereinafter described. 38 125 designates an inner inverted container whereby an inner air chamber 39 is formed and an outer air cushion 40. 41 designates

a removable plug whereby the air cushion 40 may be varied. 42 designates a valve controlled conduit communicating with a source of pressure supply, whereby the 5 cushion 40 may be varied.

43 designates a conduit provided with a valve 44 communicating with the chamber 39 and also with the combustion chamber or heat zone 4 of the furnace. 45 designates an 10 overflow pipe. 46 designates an arm connected with the member 34 to move in unison therewith and also provided with a valve stem 47, which controls the valve mechanism 48, whereby the admission of motive 15 fluid from the valve controlled conduit 49 to the motor 50 is regulated. The valve mechanism 48 admits motive fluid through conduits 51 and 52 to one side or the other of the piston 53, which latter is operatively 20 connected with the cable 54 passing over the pulleys 55 and around a pulley 56, the latter pulley being operatively connected with a damper 57. 58 designates an adjustable counterbalance for the cable 54. The valve 25 mechanism is provided with an overflow pipe 59 discharging into the container 37, whereby the liquid therein is maintained at a constant level in order to seal the lower ends of the inverted containers 36 and 38. 30 The valve mechanism 48 is constructed in such a manner that the piston 53 travels in accordance with the variation in pressure within the furnace and does not make a complete stroke unless the pressure increases or 35 decreases to a maximum extent, so that the piston may travel but a slight distance in one direction and will then stop unless the pressure within the furnace continues to change.

40 The conditions within the furnace may be varied in many ways too numerous to describe in detail herein, so that I have illustrated practical ways of varying the conditions within a furnace, for example, by 45 control of the induced draft. The mechanically induced draft, if employed, may be formed by providing the individual exhaust conduit 7 of a furnace with a by-pass 60 and a manually controlled valve 61. Located in the by-pass 60 is a suction creating device, shown as a conventional type of a blower driven by an engine 63, to which steam is conducted through the conduit 27. The engine may be provided with a governor 55 or 64 of any desired or conventional type, whereby the engine may be run at a substantially constant speed. If the valve 26 in conduit 32 is closed, the steam will pass through the conduits 28 and 27 to the engine 63, so that the engine will run at a constant speed. The governor 64 may be disconnected, however, the valve 121 closed and valve 26 opened, whereupon the speed of the engine will vary in accordance with varia-

tions in load on the furnaces since the valve 65 120 will automatically vary the amount of steam passing to the engine 63 in accordance with variations in load on the furnaces.

Any desired type of suction creating device may be employed, and in Fig. 4, the conduit 7, is provided with a steam jet 65, it being understood that a mechanically induced draft may be produced by any desired type of mechanism and still be within 75 the broad and generic scope of my invention.

In case the individual conduits 7 discharge into a main exhaust conduit 71, as seen in Fig. 8, the suction creating device, 80 such as for example 65, would be located posterior to a manually controlled damper 72, having a pulley 73 provided with a counter balance 74, said pulley 73 being adapted to be operated by a suitable cable 85 corresponding to the cable 75 seen in Fig. 1. This cable 75 passes over pulleys 76 and is connected with a pulley 77 carried by a damper 78 and provided with a counterbalance 79. 80 designates a manually controlled hand damper to close the rear end of 90 the ash pit 2.

The only difference between the construction set forth in Fig. 1 and that in Figs. 5 and 6 is that in Fig. 1, the fuel is automatically fed into the furnace, and such feeding is automatically controlled in accordance with variations in load on the furnaces, while in Figs. 5 and 6, the furnaces are hand fired, it being understood that any desired 100 type of means for varying the conditions within the furnace, such as for example, that seen in Figs. 2 and 4, is intended to be employed, if desired, in connection with the exhaust conduits seen in Figs. 5, 6, and 7, 105 and it also being understood that these exhaust conduits may discharge into a main exhaust conduit, such as 71, seen in Fig. 8, in which case the means for mechanically inducing the draft would be located in such 110 main exhaust conduit.

In order to prevent confusion, the construction in Figs. 5 to 7 inclusive have been given different reference characters, although similar parts in these figures and in Fig. 1, correspond in construction and operation. 81 designates the main draft conduit provided with a manually controlled damper 82 and also with branch conduits 83, each of which communicates with the ash-pit of 115 its respective furnace. Since each furnace is constructed and operated in a similar manner, I have deemed it to be unnecessary to describe in detail the construction and operation of each mechanism. For convenience of illustration, I have shown four furnaces 84, 85, 86 and 87, although it is to be understood that a single furnace or any 120 125

number of furnaces may be employed in carrying out my novel method. Each furnace is provided with an individual pressure regulator 88 communicating with its respective combustion chamber or heat zone 89. The construction and operation of the pressure regulators 88 correspond to that already herein set forth with reference to Figs. 1 and 3. Each pressure regulator 10 has the motor thereof operatively connected with a damper 90 in a branch conduit 83 and provided with an adjustable counterbalance 91. 92 designates a manually controlled damper, one being provided for each branch 15 conduit 83. The draft under its natural or atmospheric pressure passes into the ash-pit 93 beneath the bed of fuel 94. It will be seen that the bed of fuel in each furnace is of a different thickness, thus corresponding 20 to conditions met with in practice and furnace operations. Each furnace has a damper 95 provided with a pulley 96, adjustable counterbalance 97 and a cable 98, whereby each damper 95 may be manually opened or 25 closed when desired.

The exhaust conduits 99, in which are located the hand dampers 95, are also provided with dampers 100, which are simultaneously actuated either manually or automatically in accordance with variations in load on the furnaces. The dampers 100 are provided with pulleys 101, with which coöperate cables 102 and counterbalances 103, said cables 102 being connected with 30 pulleys 104 mounted on the shaft 105. The shaft 105 has also mounted thereon a pulley 106, around which passes or to which is connected a cable 107, said cable being also connected with a pulley on the shaft 105. The 35 cable 107, at its other end, is connected with a lever 108, corresponding to the lever 117, seen in Fig. 1, it being understood that a steam regulator corresponding to the regulator 14 in Fig. 1, is employed, connected 40 to the main header in a similar manner to that seen in Fig. 1, and operating in the same manner and including, if desired, means for mechanically inducing a draft.

The operation of my novel method of 50 regulating combustion will now be readily apparent to those skilled in this art, and is as follows:

In accordance with my novel method, I 55 am enabled to obtain substantially the same rate of combustion on a single fire or a plurality of fires with beds of fuel of different and varying thickness, so that a thick fire will produce the same result and the same amount of work as a thin fire. I am also 60 enabled to maintain a fixed and uniform difference of the pressure above and below the bed of fuel with varying rates of combustion and with different and varying thicknesses of the beds of fuel, so that a bed of fuel a 65 foot thick, for example, will perform the

same amount of work as a bed of fuel three inches more or less in thickness.

In the position of the parts seen in Fig. 1 and Figs. 5 and 6, the dampers 23 in Fig. 1, and 100 in Figs. 5, 6 and 7 are shown in 70 their wide-open position. Assuming for purposes of explanation that these dampers are closed, as well as the dampers 57 and 90, and that the load on the furnace increases or in other words, the steam pressure lowers, 75 the following action takes place. The steam regulator 14 is actuated in such a manner that the motor levers 17 and 117 are moved in a direction to open the dampers 23, or the corresponding lever 108 is moved in a 80 direction to open the dampers 100, the amount of such opening depending upon the amount of variation in load on the furnaces. This movement of the dampers 23 and 100 will change the conditions within 85 each furnace, since the exhaust conduits, such as 7 or 71, are opened to atmospheric pressure. As soon as the conditions within the furnace or the heat zone thereof begin to change in the manner just described, each 90 pressure regulator 33 or 88 will be actuated in such a manner as to operate the dampers 57 or 90 and permit an increased amount of draft for combustion to enter the ash-pit beneath the bed of fuel. On a decrease in 95 load on the furnaces or an increase in steam pressure, a reverse action to that just described takes place.

The operation of the motor controlled by the steam regulator 14 is well known in the 100 art, it being seen that the piston 112 and its adjuncts travel upwardly or downwardly, according to the pressure. Motive fluid is admitted to the valve controlled conduit 115. The admission of motive fluid from the 105 valve controlled conduit 115 to one side or the other of the piston 112, is controlled by the position of the valve stem 113. The movement of said valve stem 113, is controlled by the movement of the lever 25, 110 which moves in unison with the lever 17, so that upon the movement of the steam regulator 14, the lever 117 is moved in a corresponding direction to actuate the cable 20 and thereby simultaneously and automatically 115 actuate the dampers 23 in the different exhaust conduits 7. It will be understood that upon the movement of the steam regulator 14 and the movement of the lever 117 that the valve 120 is also actuated, so that 120 the engine 29 may be automatically controlled in accordance with variations of load on the furnace and the engine 63 may also be automatically controlled, if desired, in accordance with variations in load on the 125 furnace.

It will be understood that in case a main exhaust conduit is employed, as seen in Fig. 8, that the damper such as 23 is located between the suction creating device 65 and

the manually controlled damper 72 and will be connected with the lever 117 so as to be controlled in a similar manner to that already set forth in connection with the 5 dampers 23.

Since the bed of fuel in each furnace, in practice, varies in thickness, the resistance offered to the admission of draft for combustion varies on each furnace, and an individual 10 pressure regulator is employed for each furnace which automatically controls the introduction of draft for combustion to each individual furnace, in accordance with the resistance offered to the draft by the thickness of the bed of fuel alone, the position of the damper alone, or the resistance offered by a combination of such conditions.

In my present invention, it will be seen 20 that I have dispensed with the necessity of employing mechanically forced draft for combustion, and the furnace or furnaces are operated under an induced draft, which may be either naturally or mechanically induced, as desired, although it will be apparent that in the broad scope of my invention, either a natural or mechanically induced draft can be used.

In cases wherein the fuel is mechanically 30 fed to the fires, I preferably employ means to automatically control the operation of the engine, and in the present instance, I have shown one manner of accomplishing this result, by operatively connecting the lever 117 35 of the motor to the valve 120, whereby the passage of steam to the engine 29, which drives the traveling grate 3, is automatically controlled in accordance with the variations in load on the furnace. It will also be seen 40 that the engine 63 or the steam injector 65 may be automatically controlled in accordance with variations in load on the furnace, or may run at constant speed.

In accordance with my present method, I 45 am enabled to obtain the same amount of work from a comparatively thick bed of fuel, as seen in conjunction with the furnace 87, as I am with the beds of fuel seen in the other furnaces 84, 85 and 86.

50 The manually controlled dampers 78 or 95 are to permit an individual furnace to be cut out when desired. The automatically controlled dampers in the exhausts conduits are located posterior to the manually controlled dampers in such conduits and are located anterior to the means employed for mechanically inducing the draft.

Instead of automatically varying the conditions within the furnaces, such conditions 60 may be varied manually by leaving the dampers 23 and 100 in their wide-open position, after which the dampers 78 or 95 may be manually operated to vary the conditions within each furnace, whereupon the 65 draft for combustion will be automatically

varied in accordance with such varying conditions and in accordance with the varying thickness of the beds of fuel.

Special attention is directed to the fact that in accordance with my present invention, I

70

am enabled to eliminate entirely the manual control of the draft for combustion and maintain the same rate of combustion on all the fires regardless of the different thickness of the various fires and the entire operation is preferably automatic. Both the exhaust dampers and the fuel feeding means, when the latter are employed, are preferably automatically controlled by variations in steam pressure and the admission of draft 80 in each bed of fuel is automatically controlled by varying conditions within the heat zone of its respective furnace above the bed of fuel. As the bed of fuel increases in thickness, it is necessary to increase the intensity of draft to maintain the same rate of combustion, and in order to maintain a uniform condition of pressure above the bed of fuel, the pressure regulator, as the pressure and the combustion chamber or heat 90 zone of the furnace decreases, is actuated in a direction to increase the intensity of draft below the bed of fuel and thereby increase the combustion. By such means, I maintain a fixed and constant difference between the 95 pressures above and below the bed of fuel and substantially the amount of air necessary to support the combustion to meet the demands for steam or load on the furnace will be supplied and no more. Each fire is 100 thus made to perform its share of the work, the result of which is that a maximum furnace efficiency is obtained, which is not interfered with by the fireman or engineer attempting to manually control the dampers, 105 which control introduction of draft beneath each bed of fuel.

In methods heretofore employed in this art, it has been deemed impracticable to obtain a uniform rate of combustion in each 110 furnace owing to different causes, such as for example, the difference in thickness of the different fires, the constantly changing thickness of all fires, and the inattention of a fireman to properly adjust the hand damper admitting and controlling the draft to meet the requirements of the changing conditions of each fire.

In my present invention, a thick fire offering more resistance to the draft automatically receives a greater intensity of draft in the ash-pit, while the draft on a thin fire is correspondingly cut down.

I have referred herein to draft pressure of tension, but is to be understood that the 125 draft introduced beneath the bed of fuel for primary combustion is at its natural pressure or atmospheric pressure and the pressure in the combustion chamber of heat zone of the furnace is a relative pressure but 130

lower than atmospheric, and is commonly referred to as the vacuum above the fire.

I have deemed it unnecessary to illustrate and describe in detail a specific construction employed to carry out my novel method in case liquid or gaseous fuel or a combination of such are employed instead of solid fuel or any combination of solid, liquid or gaseous fuel, since the manner of carrying out the method is the same as herein already described and will be clearly understood by any one skilled in this art.

It will be seen from Fig. 5 that the position of the dampers 90 vary in accordance with the thickness of the bed of fuel, the furnace 87 having its damper 90 wide open, while the dampers 90 in the other furnaces are partially closed, depending upon the thickness of each bed of fuel.

20 It will be understood from Fig. 1 that valve controlled conduits 109, 110 and 111 lead from the steam conduit 28 to the engines of the fuel feeding means of the different furnaces so that the fuel feed of each 25 furnace is automatically controlled in accordance with variations in load on the furnaces.

Having thus described my invention, what I claim as new and desire to secure by Letters Patent, is:—

30 1. The method of regulating combustion in a furnace operating under an induced draft, which consists in varying the pressure within the furnace in accordance with variations of load on the furnace, and automatically regulating the introduction of draft under its natural or atmospheric pressure in accordance with the variations of pressure thus produced within the furnace.

40 2. The method of regulating combustion in a furnace operating under an induced draft, which consists in varying the pressure within the furnace in accordance with variations of load on the furnace, and automatically regulating the introduction of draft under its natural or atmospheric pressure in accordance with the variations of pressure thus produced within the furnace, and in accordance with the varying resistance offered the introduction of the draft beneath 50 the bed of fuel.

55 3. The method of regulating combustion in a furnace operating under an induced draft, which consists in mechanically inducing a draft, varying the pressure within the furnace in accordance with variations of load on the furnace, and automatically regulating the introduction of draft under its natural or atmospheric pressure in accordance with the variations of pressure thus produced within the furnace.

60 4. The method of regulating combustion in a furnace operating under an induced draft, which consists in varying the pressure

within the furnace in accordance with variations of load on the furnace, automatically regulating the introduction of draft under its natural or atmospheric pressure in accordance with the variations of pressure thus produced within the furnace, and automatically varying the fuel feed in accordance with variations in load on the furnace.

5 5. The method of controlling combustion in furnaces, which consists in varying the pressure above the fire to vary the rate of combustion on all the fires simultaneously and proportionately to variations of load on the furnaces, and varying the admission of draft for combustion under its natural or atmospheric pressure, to maintain an equal 75 rate of combustion on all the fires, which is substantially constant for varying thicknesses of the beds of fuel.

6. The method of controlling combustion in furnaces, which consists in varying the rate of combustion on all the fires, simultaneously and proportionately to variations of load on the furnaces to vary the conditions of pressure within each furnace, and then automatically varying by means of such variations in pressure the introduction of draft for combustion under atmospheric pressure to each individual fire in accordance with the thickness of its bed of fuel to maintain an equal rate of combustion on all the fires.

7. The method of controlling combustion in furnaces, which consists in varying the rate of combustion on all the fires, simultaneously and proportionately to variations of load on the furnaces to vary the conditions of pressures within each furnace, then automatically varying by means of such variation in pressure the introduction of draft for combustion under atmospheric pressure to each individual fire in accordance with the thickness of its bed of fuel to maintain an equal rate of combustion on all the fires, and automatically varying the fuel feed in accordance with variations of load on the furnaces.

8. The method of controlling combustion in furnaces, which consists in mechanically inducing a draft posterior to the fire, automatically varying the effect of such draft on the combustion chamber to vary the pressure within each furnace above its bed of fuel, and then utilizing the variations in the pressure thus produced to automatically control the admission beneath the bed of fuel of draft under its natural or atmospheric pressure.

9. The method of controlling combustion in furnaces, which consists first in automatically varying the conditions within the furnace in accordance with variations of load on such furnace, and then utilizing the varying conditions within the furnace to automatically control the introduction beneath

the bed of fuel of draft under its natural or atmospheric pressure and in accordance with the resistance offered such draft.

10. The method of regulating combustion in a furnace, which consists in mechanically inducing a draft in the exhaust conduit of the furnace, automatically controlling the draft inducing mechanism, controlling the passage of unconsumed products of combustion through said conduit in accordance with variations in load on the furnace to vary conditions within the furnace, and then utilizing the varying conditions within the furnace to automatically control the introduction of draft for combustion beneath the bed of fuel.

11. The method of regulating combustion in furnaces, which consists in simultaneously varying the pressures within all the furnaces in accordance with variations in load on all 20 the furnaces, and utilizing the varying pressure in each furnace to automatically control the introduction of draft for combustion under atmospheric pressure to the fire of its respective furnace, and automatically controlling the feed of fuel to all of the furnaces. 25
